UNITED STATES PATENT OFFICE.

ROBERT R. HUGHES, JR., OF NEW YORK, N. Y., ASSIGNOR TO UNION SPECIAL MACHINE COMPANY, OF CHICAGO, ILLINOIS, A CORPORATION OF ILLINOIS.

SHELL-STITCH SEWING-MACHINE.

1,291,526.

Specification of Letters Patent. Patented Jan. 14, 1919.

Application filed September 16, 1915. Serial No. 51,022.

To all whom it may concern:

Be it known that I, ROBERT R. HUGHES, Jr., a citizen of the United States, residing at New York, in the county of New York, 5 State of New York, have invented certain new and useful Improvements in Shell-Stitch Sewing-Machines, of which the following is a description, reference being had to the accompanying drawing and to the 10 figures of reference marked thereon.

The invention relates to new and useful improvements in sewing machines, and more particularly to the stitch-forming mechanism of a machine adapted to form shell 15 stitches.

An object of the invention is to provide a stitching mechanism wherein a thread hook, without any latch, may be used to coöperate with the needle in concatenating the thread 20 loops.

A further object of the invention is to provide a stitch-forming mechanism of the above character wherein the hook coöperating with the needle above the work support 25 is oscillated about a longitudinal axis for positioning the hook to engage the needle thread and for positioning the hook to shed the previously formed needle loop therefrom.

30 A still further object of the invention is to provide a stitch-forming mechanism of the above character wherein the hook coöperating with the needle above the work support is mounted upon a support which 35 is moved endwise and which is oscillated for properly positioning the hook so that a loop of needle thread extending beneath the work support may be carried to the edge of the fabric and a loop of needle thread 40 from above the work support carried by said hook through said previously formed loop.

A still further object of the invention is to provide a machine of the above character with a feeding mechanism for feeding the 45 fabric, which feeding mechanism may be controlled so as to shift the fabric after certain groups of stitches have been formed.

In the drawings, which show by way of 50 illustration one embodiment of the invention:—

Figure 1 is a front view of a portion of a machine having my improvements applied thereto;

Fig. 2 is a view, partly in vertical section and partly in end elevation, of said machine;

Fig. 3 is a view, partly in horizontal section and partly in plan, showing the feeding mechanism, the hook coöperating with the needle beneath the work support, the hook 60 coöperating with the needle above the work support, and the mechanisms for operating the same;

Fig. 4 is a vertical sectional view through the feed-controlling cam and the operating 65 parts therefor;

Fig. 5 is a detail in side elevation of the feed dog and supporting bar therefor;

Fig. 6 is a detail in side elevation showing the main feed bar and the cam for rais- 70 ing and lowering the same;

Fig. 7 is a detail in side elevation of the spring for holding the feed dog in ineffective position;

Fig. 8 is a view showing, more or less dia- 75 grammatically, the needle and the coöperating hooks at the time when the lower hook is first entering the needle loop;

Fig. 9 is a similar view showing the up- 80 per hook entering the needle loop carried by the lower hook;

Fig. 10 is a similar view showing the needle loop shed from the lower hook and the upper hook passing into the same for engagement with the needle thread above 85 the work;

Fig. 11 is a similar view showing the hook in engagement with the needle thread above the work support;

Fig. 12 is a similar view showing the up- 90 per hook in position for shedding the lower needle loop and drawing the upper needle loop therethrough; and

Fig. 13 is a detail view of the stitched 95 fabric.

The invention consists generally in a sewing machine having a thread carrying needle with which a hook coöperates beneath a work support for forming the needle thread into a loop, and wherein a second hook enters this formed needle loop and engages the needle thread above the work support, forming the same into a loop which is drawn through the needle loop from beneath the work support. The lower thread 100 hook is oscillated back and forth, while the 105

upper thread hook is moved endwise and is oscillated so as to position the same for engagement with the needle thread and for properly shedding the needle loop from the shank of the hook. The feeding mechanism is operated so as to feed the fabric after certain groups of stitches have been formed. This feeding mechanism is adjustable so that the time of feed may be varied, thus varying the number of stitches formed in each completed shell before the fabric is positioned for forming the next shell.

Referring more in detail to the drawings, I have shown my invention applied to a sewing machine having a bed plate 1 carrying an overhanging arm 2 in which a needle bar 3 reciprocates, carrying a needle 4. The needle 4 is supplied with a needle thread *n*.

Cooperating with the needle beneath the work support is a lower thread hook 5. This thread hook is carried by a support 6 which is pivoted at 7 to a suitable bracket 8 carried by the bed plate 1. This support 6 is oscillated by a link 9 which is pivoted at 10 to the support and is connected at its other end to a crank 11 carried by a disk 12 mounted to rotate on a bearing carried by the bracket 13 which supports the main shaft 14. A beveled gear 15 is attached to the disk 12, and this beveled gear meshes with a second beveled gear 16 which is fixed to the shaft 14. As the shaft 14 rotates, the disk 12 will rotate and, through the crank 11, oscillate the thread hook 5 back and forth. This thread hook is timed so as to move between the needle thread and the body of the needle when said needle is substantially at the lower end of its stroke and forms the needle loop beneath the work support which work support is indicated at 17 in the drawings.

Cooperating with the thread hook 5 beneath the work support and the needle 4 above the work support is a second or upper thread hook 18. This thread hook is mounted in a socket in a looper supporting shaft 19 and is held therein by a set-screw 20. The shaft 19 is journaled in a sleeve 21 so that said shaft may not only oscillate with the sleeve but move freely endwise therein. Said shaft is also journaled in a bearing 22. The shaft is moved endwise by means of a link 23 which is pivoted at 24 to a sleeve 25 held from endwise movement on the looper shaft by fixed collars 26. The link 23 is pivoted to an arm 27 carried by a transverse shaft 28 which is journaled in a bracket 29. This shaft carries a second arm 30 which is connected to an eccentric strap 31 cooperating with an eccentric on the main shaft 14.

The bearing 22 is suspended from an arm 32 mounted on a shaft 33 journaled in a bracket 34. A link 35 is pivoted at its up-

per end to said arm 32 and is pivoted at its lower end to this bearing 22. The bearing 22 has a groove in its side face into which extends an arm 36 which is rigidly attached to a lug 37 by screws 38. A bar 39 which is secured to the bearing 22 by screws 40 holds the arm in the groove. The sleeve 21 in which the looper shaft 19 is mounted is pivoted at 41 to its supporting bracket 29, and the arm 36 and the groove in which it works are both curved about this center 41. Splined to the looper shaft 19 is a gear 42. This gear 42 meshes with a rack 43 which is secured by screws 44 to the bracket 34. The gear 42 is held from endwise movement relative to the shaft 19 by a yoke 45 which is fixed to the bearing 22 and is provided with pins or balls running in a groove 46 formed in the hub of the gear 42. The rack 43 is also curved about the center 41. The shaft 33 is oscillated by an arm 47 which is connected to a pitman 48 which, in turn, cooperates with an eccentric on the main shaft 14.

The fabric is held on the work support 17 by a presser foot 49 which is fixed to a presser bar 50 mounted in the overhanging arm of the machine. A feed dog 51 engages the fabric underneath the presser foot 49 and feeds the same so as to properly position the fabric for the formation of the shell stitches. This feed dog 51 is preferably formed integral with a bar 52 which is supported by a main feed bar 53. This main feed bar 53 is pivoted at 54 to the feed rocker 55 which, in turn, is pivoted at 56 to the bed plate 1. The feed rocker 55 is moved back and forth by a link 57 which is connected to an adjustable crank pin 58 carried by the end of the main shaft 14. The main feed bar 53 is raised and lowered by an eccentric 59 mounted on the shaft 14. This eccentric engages a hardened plate 60 secured to the under face of the main feed bar and a bracket arm 61 which is also secured to this main feed bar. The main feed bar 53 is formed with a groove or recess in its upper face extending substantially from end to end thereof and the bar 52 carrying the dog 51 is located in this recess. Said bar 52 is secured to the main feed bar by a pivot pin 62. A spring 63 is secured to the upper face of the main feed bar by screws 64, and this spring rests upon the upper face of the bar 52 and holds the feed dog 51 depressed. The main feed bar 53 and the eccentric which raises and lowers the same are so formed that, when the feed dog 51 is depressed by this spring 63, the feed dog will move back and forth with the movement of the feed bar 53 without engaging the material. The feed bar is raised into engagement with the material by a controlling cam 65. This controlling cam 65 is carried by a shaft 66 mounted in a bracket 67 secured to the bed 130

plate 1. Said controlling cam is mounted on one end of the shaft, as shown in Fig. 4, and the shaft is rotated by a ratchet wheel 68 which is rigidly secured to the other end of the shaft. The ratchet wheel is propelled by a pawl 69. This pawl is pivoted by a pin α to an arm 70 mounted so as to oscillate freely on the shaft 66. A spring 71, shown in dotted lines in Fig. 2, normally holds the pawl in engagement with the ratchet wheel 68. The arm 70 through the medium of a pin is connected by a link 72 to an adjustable stud 73 fixed to a bracket arm 74 mounted on the feed rocker 55. This stud 73 is mounted in a segmental slot 75 in the arm 74. By adjusting the stud upwardly in the slot, the throw of the arm 70 may be increased, while an adjustment of the stud downwardly in the slot decreases the throw of the arm. By this adjustment, the throw of the pawl 69 may be varied, and thus the time interval, when the controlling cam 65 becomes effective to raise the feed dog into engagement with the fabric, may be varied. The bar 52 is formed with a downwardly projecting lug 76 which projects through a slot 77 in the main feed bar 53, and this projecting lug lies in the path of travel of the controlling cam 65. As herein shown, this controlling cam is formed in two parts which are equally spaced. When the controlling cam 65 strikes the lug 76, then the feed bar 52 will be turned about its pivotal connection so as to raise the feed dog 51 into engagement with the fabric. That is to say, when the feed dog is raised by the controlling cam, then the four motions given to the main feed bar 53 cause the feed dog to become effective to feed the material as long as this bar is raised. As soon as the controlling cam 65 passes from beneath the lug 76, then the spring will throw the feed bar downward and position the feed dog so that it becomes ineffective in its movements. From the above, it will be apparent that I may control the feed dog which is moved back and forth for each rotation of the shaft so that said feed dog will only feed the material after a certain number of rotations of the shaft. Thus, the fabric may be positioned for the formation of the shell stitch, and the needle will enter the fabric substantially in the same place for a plurality of reciprocations, after which the fabric is moved and the needle positioned for the next shell. By varying the throw of the pawl which turns the ratchet wheel moving the controlling cam, I may vary the period of time the feed dog remains in its ineffective position, and consequently vary the number of stitches formed in each shell, that is to say, the pawl may be caused to feed two, four or six teeth at every stroke, and by adjusting the throw of the pawl groups of stitches varying from four stitches to

eighteen or twenty stitches for each shell may be made. By adjusting the crank pin 58, the feed travel may be varied and consequently the distance between successive shells may be varied.

In the operation of my device, the needle passes through the fabric on the work support and rises slightly to form the needle loop and then the lower hook 5 moves into said loop and carries the same toward the edge of the fabric. At the same time the hook 18 is being lowered and turned. When the hook 5 reaches substantially the forward end of its stroke, the hook 18 is completely lowered and turned and is substantially in the position shown in Fig. 9. This hook 18 has a beak 78 and has a point 79 which is slightly deflected upwardly relative to the beak 78 and laterally relative to said beak, as shown in Figs. 9 and 10. An oscillation of the shaft 33 causes the hook to rise up against the under face of the needle loop, as shown in Fig. 9, and to enter the needle loop when said hook moves forward, as shown in Fig. 10. The forward movement of the hook is caused, as above noted, by the oscillation of the shaft 33 which reciprocates the looper shaft 19 in its bearings. As the looper shaft 19 is raised to bring the hook 18 above the plane of the work support, the gear 42 running on the rack 43 will oscillate the hook so as to bring its beak 78 into substantially a horizontal plane, as shown in Fig. 10. The needle rises to the upper end of its stroke, as shown in Fig. 11, and this beak 78 engages the thread between the needle eye and the fabric, the hook lying substantially horizontal at the time it engages the thread. The hook 18 is then moved backward and as it is lowered it is also rotated so as to bring the beak into the position shown in Fig. 12, and this permits the hook to move out of the first formed needle loop without engaging the strands thereof. In other words, by this oscillation of the hook, I am enabled to move the hook through one needle loop and engage the needle thread to form another needle loop and draw this second needle loop through the first needle loop without the use of a loop-shedding latch. The hook 18, when it sheds the lower needle loop, as shown in Fig. 12, carries the upper loop through this lower needle loop and, when this hook moves forward to enter the next needle loop formed beneath the work support, that is, to the position shown in Fig. 9, this upper thread loop will be still retained by the thread hook 18 and the movement of the thread hook 18 underneath the new needle loop lifts this new needle loop up through the previously formed upper needle loop and sheds this upper formed needle loop from the hook. In other words, first a needle loop is formed above the material and carried through a needle loop formed be-

neath the material, after which the loop formed beneath the material is carried through the next needle loop formed above the material. The curving of the point of the hook 18 serves to retain this lower needle loop on the shank thereof when the hook is moved into the lower needle loop, as shown in Figs. 9 and 10.

In Fig. 13 of the drawings, I have shown the fabric at *f* and the loops, which are interlocked to form the shell stitches, are indicated at *s*. The needle punctures are indicated at *n'*. It will be noted that the needle enters the fabric at the points indicated at *n'* and a series of concatenated loops is formed for each position of the needle. After a certain number of stitches have been formed, then the feed becomes effective to position the fabric for the next stitch position and thus a series of interlocked loops are grouped about each needle position, forming what is known in the art as shell stitches.

It will be obvious that minor changes in the details of construction and the arrangement of parts may be made without departing from the spirit of the invention, as set forth in the appended claims.

Having thus described my invention, what I claim as new and desire to secure by Letters-Patent is:—

1. The combination of a work support, a thread carrying needle, a thread hook co-operating with the needle beneath the work support, a second thread hook adapted to pass through the loop formed by the first-named thread hook and engage the needle thread above the work support to form a loop thread therein and draw the same through the first-named thread loop.

2. The combination of a work support, a thread carrying needle, a thread hook, means for operating said thread hook for engaging the needle thread beneath the work support to form a thread loop therein, a second thread hook, means for reciprocating said last-named thread hook and for oscillating the same whereby said hook is caused to enter the loop formed beneath the work support, engage the needle thread above the work support, form a loop therein, and draw the same through the first-named loop.

3. The combination of a work support, a thread carrying needle, a thread hook co-operating with the needle beneath the work support, a thread hook co-operating with the needle above the work support, means for operating said last-named thread hook whereby a loop is formed in the needle thread above the work support and the loop of thread formed in the needle thread beneath the work support by the first-named thread hook is engaged by said second thread hook and carried through the needle loop formed above the work support.

4. The combination of a work support, a thread carrying needle, a thread hook co-operating with the needle beneath the work support, a thread hook co-operating with the needle above the work support, means for operating said last-named thread hook whereby the same is reciprocated and oscillated and caused to engage the needle thread above the work support and form a loop therein, also to engage the needle loop from beneath the work support and carry the same through the needle loop formed by said last-named thread loop above the work support, and also to form another thread loop in the needle thread above the work support and carry the same through said needle loop formed beneath the work support.

5. The combination of a work support, a thread carrying needle, a thread hook co-operating with the needle beneath the work support, a thread hook having a laterally deflected point adapted to enter the needle loop formed beneath the work support, and a hook in rear thereof adapted to engage the needle thread above the work support, means for operating said last-named thread hook whereby the same is reciprocated and oscillated and caused to engage the needle thread above the work support and form a loop therein, also to engage the needle loop from beneath the work support and carry the same through the needle loop formed from the needle thread above the work support, and also to form another thread loop in the needle thread above the work support and carry the same through said needle loop formed beneath the work support.

6. The combination of a work support, a thread carrying needle, a thread hook co-operating with the needle beneath the work support, a thread hook co-operating with the needle above the work support, said last-named thread hook having its point deflected away from its beak and laterally of its beak to assist in retaining the needle loop from beneath the work support on said thread hook.

7. The combination of a work support, a thread carrying needle, a thread hook co-operating with the needle beneath the work support, means for oscillating said thread hook, an upper thread hook co-operating with the needle above the work support and with the first-named thread hook beneath the work support, means for reciprocating said upper thread hook and for oscillating the same whereby the beak of said upper thread hook is positioned horizontally for engagement with the needle thread and is positioned substantially vertically to facilitate the shedding of the under thread loop from the shank of said upper hook, said upper thread hook having its point bent outwardly away from the beak and laterally of the beak to assist in retaining the needle loop.

thread loop when said upper thread hook is entering the needle loop from beneath the work support.

8. The combination of a work support, a thread carrying needle, a thread hook co-operating with the needle beneath the work support, a thread hook co-operating with the needle above the work support and with said hook beneath the work support, a shaft carrying said last-named thread hook, a pivoted sleeve in which said shaft is mounted to reciprocate and oscillate, means for reciprocating the shaft in said sleeve, and means for oscillating the shaft as it is reciprocated.

9. The combination of a work support, a thread carrying needle, a thread hook co-operating with the needle beneath the work support, a thread hook co-operating with the needle above the work support and with said hook beneath the work support, a shaft carrying said last-named thread hook, a pivoted sleeve in which said shaft is mounted to oscillate and to reciprocate, means to reciprocate said shaft, a gear splined on said shaft, a stationary rack engaged by said gear, and means for bodily swinging said shaft, said gear operating to oscillate the shaft during its bodily swinging movement.

10. The combination of a work support, a thread carrying needle, a thread hook co-operating with the needle beneath the work support, a thread hook co-operating with the needle above the work support and with said hook beneath the work support, a shaft carrying said last-named thread hook, a pivoted sleeve in which said shaft is mounted to reciprocate and oscillate, means for reciprocating the shaft, a bearing between said sleeve and said hook for said shaft, means for raising and lowering said bearing, a guide curved about the pivot of said sleeve as a center for guiding said bearing in its up and down movements.

11. The combination of a work support, a thread carrying needle, a thread hook co-operating with the needle beneath the work support, a thread hook co-operating with the needle above the work support and with said hook beneath said work support, a shaft carrying said last-named thread hook, a pivoted sleeve in which the shaft is mounted to reciprocate and oscillate, means for reciprocating the shaft, a bearing between the sleeve and said hook for the shaft, means for raising and lowering said bearing, a stationary rack curved about the pivot for said sleeve as a center, a gear splined to said shaft and carried by said bearing and meshing with said rack for oscillating said shaft.

12. The combination of a work support, a thread carrying needle, a thread hook co-operating with said needle beneath the work support, a thread hook co-operating with the needle above the work support and with said hook beneath the work support, said implement having a thread en-

hook beneath the work support, means for reciprocating and oscillating said last-named thread hook whereby loops are formed in the needle thread, which loops are locked successively one with the other, and a feeding mechanism including a feed dog, means for reciprocating said feed dog, and means for rendering said feed dog ineffective to engage the fabric during a plurality of reciprocations of the needle.

13. The combination of a work support, a thread carrying needle, a thread hook co-operating with the needle beneath the work support, a thread hook co-operating with the needle above the work support and with said hook beneath the work support, means for reciprocating and oscillating said last-named thread hook whereby loops are formed in the needle thread beneath the work support which loops are locked successively one with the other, and a feeding mechanism including a feed dog, means for reciprocating said feed dog, and means for rendering said feed dog ineffective to engage the fabric during a plurality of reciprocations of the needle, said last-named means including devices which may be adjusted for varying the time interval when said feed dog becomes effective to feed the fabric.

14. The combination of a work support, a needle, a thread hook, means for operating the thread hook whereby the same is caused to pass into a needle loop formed beneath the work support, engage the needle thread above the work support and draw the same through the first named needle loop for forming shell stitches and a feeding mechanism for feeding the material, including means for giving the material a feeding movement after a predetermined number of shell stitches have been formed and means whereby the length of the feed movement may be varied.

15. The combination of a work support, a needle, a thread hook, means for operating the thread hook whereby the same is caused to pass into a needle loop formed beneath the work support, engage the needle thread above the work support and draw the same through the first named needle loop for forming shell stitches and a feeding mechanism for feeding the material, including means for giving the material a feeding movement after a predetermined number of shell stitches have been formed and means for varying the time of movement of the feed mechanism whereby the number of shell stitches between the feed movements may be varied.

16. A sewing machine including in combination, a work support, a needle, a thread hook co-operating with the needle beneath the work support, a thread taking implement co-operating with the needle above the work support and with said hook beneath the work support, said implement having a thread en-

- gaging hook, means for moving said implement above and below the work support and for oscillating the implement whereby said hook is substantially horizontal while engaging the needle thread above the work support and is substantially vertical while passing into and out of the needle loop formed beneath the work support.
17. A sewing machine including in combination, a work support, a needle, a thread hook coöperating with the needle beneath the work support, a thread taking implement coöperating with the needle above the work support and with said hook, said thread taking implement having a hook for engaging the needle thread, means for engaging the needle thread, means for moving the thread taking implement bodily up and down and means for oscillating said thread taking implement.
18. A sewing machine including in combination, a work support, a needle, and a loop-forming implement coöperating with the needle beneath the work support, a second loop-forming implement coöperating with the first-named loop-forming implement beneath the work support and with the needle above the work support, said second-named loop-forming implement having a hook on one face thereof for engaging the needle
- thread above the work support and an upturned point for engaging the loop formed in the needle thread beneath the work support whereby said second-named loop-forming implement may pass through the loop formed in the needle thread beneath the work support by the first-named loop-forming implement and engage the needle thread above the work support and form a loop therein.
19. A sewing machine including in combination, a work support, a needle, a hook coöperating with the needle beneath the work support, a loop-forming implement coöperating with the hook and with the needle above the work support, said loop-forming implement having a hook on one side face thereof, means for raising and lowering said loop-forming implement, and means for oscillating the same, said oscillating means including devices whereby the hook is given a dwell in its upper and lower position, and means for moving said loop-forming implement bodily endwise.

In testimony whereof, I affix my signature, in the presence of two witnesses.
